CLAIM

I claim the ornamental design for a root shovel, as shown and described.

DESCRIPTION

FIG. 1 is an isometric view of a root shovel.

FIG. 2 is a front view of the root shovel.

FIG. 3 is a back view of the root shovel.

FIG. 4 is a right side view of the root shovel.

FIG. 5 is a left side view of the root shovel.

FIG. 6 is a top view of the root shovel; and,

FIG. 7 is a bottom view of the root shovel.

It is noted that the phantom lines depicted in the figures are intended for the purposes of illustration only and are not a part of the design.
